(57) **CLAIM**

The ornamental design for an automobile interior, as shown and described.

DESCRIPTION

FIG. 1 is a front view of an automobile interior showing our new design;

FIG. 2 is a driver-side perspective view thereof;

FIG. 3 is a passenger-side perspective view thereof; and,
FIG. 4 is a top plan view.

It will be understood that the dashed lines presented in the drawings are for illustration only, and do not form a part of the claimed design.
